PISTOL GRIP

Toivo J. Vahala, New York, N. Y.

Application March 24, 1950, Serial No. 8,751

Term of patent 3½ years

(Cl. D30—1)

To all whom it may concern:

Be it known that I, Toivo J. Vahala, a citizen of the Republic of Finland, residing at New York, city, county, and State of New York, have invented a new, original, and ornamental Design for a Pistol Grip, of which the following is a specification, reference being had to the accompanying drawing, forming a part hereof.

In the drawings:

Fig. 1 is a view in elevation looking at the left-hand side of the pistol grip, the metal parts of the pistol being shown in dotted lines.

Fig. 2 is a similar view of the right-hand side of the pistol grip.

Fig. 3 is a rear view.

Fig. 4 is a front view of the same, and

Fig. 5 is a sectional view on the line 5—5 of Fig. 1.

The dotted line showing in Fig. 1 is for illustrative purposes only.

I claim:

The ornamental design for a pistol grip, as shown and described.

TOIVO J. VAHALA.
